(57) **CLAIM**

The ornamental design for a pod for an electronic vaporizer, as shown and described.

DESCRIPTION

FIG. 1 is a perspective front view of a pod for an electronic vaporizer.

FIG. 2 is a front view of the pod for electronic vaporizer of FIG. 1.

FIG. 3 is a rear view of the pod for electronic vaporizer of FIG. 1.

FIG. 4 is a right side view of the pod for electronic vaporizer of FIG. 1.

FIG. 5 is a left side view of the pod for electronic vaporizer of FIG. 1.

FIG. 6 is a top view of the pod for electronic vaporizer of FIG. 1.

FIG. 7 is a bottom view of the pod for electronic vaporizer of FIG. 1.

FIG. 8 is a front perspective view of the pod for electronic vaporizer of FIG. 1, shown assembled with an electronic vaporizer.

FIG. 9 is a front exploded view of the pod and electronic vaporizer assembly of FIG. 8.

FIG. 10 is a rear perspective view of the pod and electronic vaporizer assembly of FIG. 8; and,

FIG. 11 is a rear exploded view of the pod and electronic vaporizer assembly of FIG. 8.

In the drawings, the claimed design is defined by the shaded surfaces; evenly spaced and dash-dot broken lines immediately adjacent shaded surfaces represent boundaries of the claim and form no part thereof; all other broken lines depict environmental subject matter that form no part of the claim.

1 Claim, 9 Drawing Sheets
